UNITED STATES PATENT OFFICE.

JOHN F. COURSON, OF PITCAIRN, PENNSYLVANIA.

DRAFT-GEAR.

1,071,399.

Specification of Letters Patent. Patented Aug. 26, 1913.

Application filed December 11, 1911. Serial No. 665,011.

To all whom it may concern:

Be it known that I, JOHN F. COURSON, a citizen of the United States, residing at Pitcairn, in the county of Allegheny and State of Pennsylvania, have invented certain new and useful Improvements in Draft-Gears, of which the following is a specification.

My invention consists of an improvement in friction draft gears or rigging for railway cars, etc., and it has for its object to provide a draft gear of simple construction and high efficiency designed to utilize the wedging and releasing qualities of wedge blocks between a central buffing member and surrounding friction members, said wedge blocks preferably having faces disposed at varying angles adapted to positively release and to exert great frictional engagement, in combination with the usual co-acting parts of such equipments.

The invention relates particularly to the construction, arrangement and mounting of the intervening secondary wedge blocks or pieces.

In the accompanying drawings illustrating the invention—Figure 1 is a view of the mechanism in side elevation, partly in section, showing the parts in extended position. Fig. 2 is a cross section on the line II. II. of Fig. 1. Fig. 3 is a similar cross section, showing a slight modification in the construction of the centering key. Fig. 4 is an enlarged sectional detail view on the line IV. IV. of Fig. 5, showing a modified arrangement of the secondary wedge blocks. Fig. 5 is a cross section taken on the line V. V. of Fig. 4. Fig. 6 is a perspective detail view of one of the wedge blocks of the construction shown in Figs. 1, 2 and 3. Figs. 7 and 8 are similar views, showing the female and male members of the wedge blocks used in the construction illustrated in Fig. 4. Fig. 9 is a detail view of the centering key illustrated in Figs. 1 and 2. Fig. 10 is a detail view of the centering key illustrated in Fig. 3.

In the drawings, 2 represents the draw-bar of the coupler fixedly connected with 50 the yoke 3 by transverse rivets 4 in the manner customary in this art, said yoke embracing the casing or cylinder 5 at top and bottom, as shown, the yoke and casing being located between the usual draft sills 55 of the car framing.

The numerals 6 and 7 designate a filling block and follower plate respectively, set against the rear end of casing 5 and against the outer end of block 6 bears the rounded end 8 of the strap 3, the filling block being 60 preferably secured to the end of the strap, as indicated at 9.

The numeral 10 designates a follower plate, like plate 7. Each of these plates extends out laterally at each side of the 65 yoke 3 and bears against the usual front and back stops of any suitable construction secured to the center sills and which provide abutments against pulling and buffing strains respectively, as is well understood. 70

A plurality of friction blocks or shoes 13, outwardly cylindrical when assembled, of segmental form, are inserted within the cylinder 3 and bear by their inner ends against a spring 14, which in turn bear backwardly 75 against the inner end of the cylinder 5.

The central pressure bar 11, provided with an inner blunt wedge terminal 15, bears by its outer end against the follower 10. Surrounding the wedge terminal 15 80 and intervening between it and the shoes 13, are a plurality of secondary wedges 16 of any desired number. The inner faces of the friction blocks or shoes 13 are preferably tapered, as at 17, at an acute angle to 85 the longitudinal center of the drawbar, the outer faces of the secondary wedge blocks 16 being similarly tapered at the same angle, as at 18, and contacting therewith.

The wedge terminal 15 of central pressure bar 11 is provided with inclined wedge faces at a more abrupt, blunt or obtuse angle to the longitudinal center of the drawbar, and engage the inner correspondingly inclined, more obtuse faces 20 of secondary wedge 95 blocks 16. The inner ends of the secondary wedge blocks 16 are adapted to be maintained against collapsing, when the apparatus is extended, or in any operative position, for which purpose they are positively braced 100 apart at their inner ends and also retained against longitudinal shifting. In one form of the invention I have provided for such action by inserting between the wedges an intermediate centering key or support 21. 105 Said key, in the construction shown in Figs. 1, 2 and 9, is substantially rectangular, having its edges and corners rounded, as shown, and is inserted between the inner terminals of the secondary wedges 16, which are pro- 110

vided with receiving recesses 22, between inwardly extending lips 23, 24, as clearly shown.

In Figs. 3 and 10, I show a modified construction of key 21' made in the form of a round disk, the edges of which are similarly rounded and adapted to seat in similar receiving grooves and to perform the same function.

10 In the construction shown in Figs. 4 and 5, the intermediate wedge blocks 16' are, as are all the other parts, made of the same proportions and corresponding angles, but their number is reduced, and they consist 15 of a male and female member respectively, having opposing acute angle faces 17' inter-fitted with the inner faces of two oppositely located frictional shoes 13', which shoes bear by their curved outer surfaces against 20 the interior wall of the cylinder.

In place of the loose centering key 21 or 21', one of the secondary wedges 16' is provided with a semi-cylindrical projection 21^a extending into a receiving groove or recess 25 21^b in the opposite wedge block and providing a journal bearing for said parts. The construction of this arrangement of secondary wedge blocks is clearly illustrated in Figs. 7 and 8, and it will be observed that 30 the recess 21^b is closed at the ends and the projection 21^a sufficiently shortened to inter-fit therein, so as to entirely prevent any lateral shifting.

With either construction, the operation is 35 substantially the same. A positive bracing support for the inner ends of the wedges is provided, in the manner of a fulcrum, whereby the wedges are free to expand or collapse; especially the latter, upon release 40 of pressure.

It will be observed that the inner ends of the friction shoes 13 are flared off, as at 25 and 25^a, from a point where the bearing surface 17 terminates, somewhat in advance 5 of the supported inner tail portions of the secondary wedges 16. The purpose of such construction is to provide clearance so that in exerting pressure to create friction, either in buffering or in pulling by the separation of 10 the secondary wedges 16 by wedge 15, there will, on the release of such pressure, be no tendency to stick or bind, effecting an immediate and complete collapsing of the secondary wedges and an immediately resulting 15 release of the friction shoes 13.

The pressure exerted by the central wedge 15 will cause the secondary wedges to bear by their outer acute angles 18 tightly against the inner flat faces of the friction shoes 13, effecting a slight separation of the inner 20 ends of the secondary wedges, but not sufficient to cause any disturbance or release of the centering key 21. Said key provides a supporting abutment at all times and positively holds all of the several intermediate

wedge blocks in the same relative position longitudinally of the gear. It prevents undue tipping of the inner ends or any undesirable shifting and tends to hold the entire construction in unitary arrangement.

Having described my invention, what I claim is:

1. In a friction draft gear, the combination of a casing, a relatively movable drawbar, friction blocks engaging the casing, a buffering block engaging the drawbar, and differential angle wedge blocks interposed between the friction blocks and the buffering block provided with an intervening supporting pivotal bearing.

2. In a friction draft gear, the combination of a casing, a relatively movable drawbar, friction blocks engaging the casing, a buffering block engaging the drawbar, and differential angle wedge blocks interposed between the friction blocks and the buffering block provided at their inner ends with an intervening supporting pivotal bearing.

3. In a friction draft gear, the combination of a casing, a relatively movable drawbar, friction blocks engaging the casing, a buffering block engaging the drawbar, and wedge blocks interposed between the friction blocks and the buffering block provided at their inner ends with a key constituting pivotal bearings therefor.

4. In a friction draft gear, the combination of a casing, friction shoes having inner wedge faces and terminal non-contacting clearance spaces, a central wedge, and secondary wedges between the central wedge and said friction shoes extending inwardly of said clearance spaces and provided with an intervening supporting pivotal bearing.

5. In a friction draft gear, the combination of a casing, friction shoes engaging the casing having inner wedge faces, a central wedge, and secondary wedges between the central wedge and said friction shoes having portions extended inwardly beyond the terminals of the wedge faces of the friction shoes and provided with an intervening pivotal bearing support.

6. In a friction draft gear, the combination of a casing, a relatively movable drawbar, friction blocks engaging the casing, a buffering block engaging the drawbar, and wedge blocks interposed between the friction blocks and the buffering block provided at their inner ends with concave recesses and a pivot key.

7. In a friction draft gear, the combination of a casing, friction shoes having inner wedge faces and terminal clearance spaces, a central wedge, and secondary wedges between the central wedge and said friction shoes, said secondary wedges extending inwardly of said clearance spaces and each being provided with an inner concave recess, and a supporting and interlock-

ing key, engaging said recesses and bracing the secondary wedges apart.

8. In a friction draft gear, the combination of a casing, friction shoes engaging the 5 casing having inner wedge faces on their adjacent front portions, a central wedge, a drawbar, and secondary wedges interposed between the central wedge and said friction shoes having portions extended inwardly beyond the terminals of the wedge faces of the

friction shoes and provided with intervening bearing portions constituting a fulcrum rest for the inner ends of said secondary wedges.

In testimony whereof I hereunto affix my 15 signature in the presence of two witnesses.

JOHN F. COURSON.
